UNITED STATES PATENT OFFICE.

JAMES WILLIAM BOOTH AND THOMAS CRAVEN CORLASS, OF KEIGHLEY, ENGLAND.

LOOM LET-OFF MECHANISM.

Application filed February 23, 1926, Serial No. 89,893, and in Great Britain February 26, 1925.

This invention relates to loom left-off mechanism of the type or class wherein the retarding actions upon the warp beam are effected by chains, ropes, clamps or other 5 brake devices and which actions are gradually reduced in accordance with the diminishing diameter of the coils of warp on the warp beam. Our present invention consists in a novel construction and arrangement of 10 the devices which connect the detector member to the moving weight on the lever which effects or brings about the brake action, by which the whole mechanism may be readily fixed in position, will occupy comparatively 15 little space and will act with efficient regularity.

In order that our said invention may be readily understood, we have hereunto appended a sheet of drawings illustrative 20 thereof, to which by figures and letters, reference is made in the following description.

Fig. 1 is a rear view of sufficient of a loom to show the application of our devices to the warp beam in connection with said loom.

Fig. 2 is a plan of the parts shown by Fig. 1 with a portion of the warp beam cut away so that the parts beneath might be more clearly seen.

Fig. 3 is a similar view to Fig. 1 and shows 30 certain of our parts drawn to an enlarged scale.

Fig. 4 is an end elevation of parts shown by Fig. 3 as seen in the direction looking from right to left of said figure.

Fig. 5 is a similar view to Fig. 3 but illustrates a modification hereinafter explained.

A indicates the end frame of the loom B, B¹ the upper and lower back rails of said loom and C the warp beam.

In carrying our invention into effect we make use of a bell crank lever 2 which we arrange to have one arm *a* to carry a weight 3 while the other arm *b* extends vertically preferably in a downward direction as shown by the drawings, so that it may be coupled by any suitable connections as the rod 4^a, the chain 4, connecting rod 5, guide pulley and connecting rod 6, to levers 7, 7^a, 8 and 8^a which latter are pivoted at *d*, *d*¹ and operate in well known manner in connection with this type of let-off mechanism by said levers 8, 8^a actuating the brake blocks 9, 9^a which partly encircle the outer ends of the beams C as is well known or which might activate chafits.

The weight 3 carried by the arm *a* of the

lever 2 is arranged to slide over said arm from its outer end towards the fulcrum *f* thereof in order to decrease its power over the lever 2 as the decreasing diameter of the 60 coils of warp on the beam C proceeds.

This weight 3 is caused to automatically slide over the arm *a* of the lever 2 in a gradual manner according to the movements of the detector rollers 10 which are mounted to 65 revolve on bearings at the upper end of a sliding bar or rack 11 according to the alternative arrangements of our invention as illustrated by Fig. 1 and Fig. 5, the alternative arrangement in Fig. 5 being hereinafter 70 described.

The vertical bar 11 according to the arrangement shown by Figs. 1 to 4 is in the form of a rack the teeth of which mesh with a pinion 12 pivoted on the shaft *g* mounted upon the bearings 13 which are supported by a separate bracket 14 that will slide over a bracket 15 fixed to the lower rail B¹ at the rear of the loom. The adjustment of the bracket 13 by means of sliding the bracket 14 upon the bracket 15 is to secure the fulcrum *f* of the lever 2 in such a position as to keep the arm *a* of said lever practically horizontal throughout all the letting-off operations. 75

It will be observed that the parts supported by the fixing brackets 15, 14 and 13 may all be assembled on said brackets prior to being fixed upon the loom so that when thus assembled the whole may be mounted in position by fixing the bracket 15 to the rail B¹. 90

Upon the short shaft *g* forming the support for the pinion 12 is fixed another pinion 16 which engages with the teeth of a rack 17 that slides horizontally upon the bearings 18 as such rack 17 is moved under the recoil of the spring 19 which at all times tends to cause said rack 17 to move in the direction indicated by the arrow *x*. This is effected by the end of the spring near the shaft *g* being fixed to the bearing 13 while the other end of the spring 19 is fixed to the end of the rack 17. As the coils of warp on the beam C decrease in diameter the pull of the spring 19 causes the pinions 16 and 12 to revolve and thereby raise the rack bar 11 so as to force the detector rollers 10 against the surface of the beam C, and during such rising movement of the rack bar 11 the rack 17 will have moved as is stated in the direction indicated by the arrow *x* and will by being connected with the rod 20 to the weight 3 100

105

110

move said weight along the arm *a* of the lever 2 causing same to travel nearer to the fulcrum *f* of said lever and thereby to gradually decrease the power that said weight has 5 over the said lever 2 and consequently to decrease its power over the friction brakes 9 and 9^a.

The arm *b* of the lever 2 has mounted on it a vertical screw 21 which supports or carries 10 the end of the connecting rod 4^a closer to or further from the fulcrum *f* as the nature of the work or the power required to be exerted by the weight 3 over the brakes 9 and 9^a may demand, the further the connections 15 4, 4^a upon said arm *b* of the lever 2 are from the fulcrum *f* so will the force exerted by the lever 3 be less over the brake shoes 9 and 9^a.

The arrangement of our devices as above described enable us to mount same in such 20 a position that the detector rollers 10 may be practically vertically beneath the centre of rotation of the beam C while the mounting of the lever 2 and the other devices in connection therewith fall within the outer 25 diameter of the same beam C consequently the mounting of our devices in position upon the loom does not interfere with the useful space or gait between said loom and the one to the rear of same which has advantages for 30 many and varied purposes.

As an alternative to the employment of the racks 11 and 17 we may make use of a bar 11^a (shown by Fig. 5) for supporting the detector rollers 10 and this bar we may 35 arrange to be hollow so that a chain 22 fixed to the outer end of the sliding bar 23, which we use in place of the rack 17, may take over a guide pulley or other device in order that its outer end may be fixed to the lower end *k* 40 of the bar 11^a. This sliding bar 23 is actuated by the spring 19 as is the rack 17 so that by the spring 19 being fixed at *m* to the bracket 13 while its other end is fixed to the end of the bar 22 said spring is enabled 45 to raise by its recoil the bar 11^a as will be understood. During the horizontal movement of the bar 23 it will carry with it the connecting rod 20 which connects it to the weight 3 as is the case in our other 50 arrangement.

Such being the nature and object of our said invention what we claim is:—

1. In loom let-off mechanism, a detector for contacting with the warp on the warp beam, a vertically extending bar upon which said detector is mounted, means for connecting said vertically moving bar to a horizontally moving bar so that the one may be operated by the other, a spring attached to 55 the horizontally moving bar and to a bracket which supports the said horizontally and vertically moving bars, a lever pivoted upon the same bracket and arranged to receive a weight, said weight formed to slide over 60 said lever, means for coupling the weight 65

to the horizontally sliding bar, means for coupling the weighted lever to levers which actuate the brake applying devices to the warp beam and said warp beam.

2. In loom let-off mechanism, a detector 70 for contacting with the warp on the warp beam, a vertically extending bar upon which said detector is mounted, said bar having rack teeth formed upon it, a toothed pinion engaging said rack teeth, another toothed 75 pinion fixed to the former, a horizontally moving rack bar engaging with the second pinion, a supporting bracket upon which said rack bars and pinion are mounted to operate, a spring connected to the horizontally moving rack bar and to the bracket, a connection from the horizontally moving rack bar to a sliding weight, said sliding weight, a lever upon which said weight is arranged to slide, said lever being mounted 80 upon the bracket which supports the vertically and horizontally moving rack bars and toothed pinions, a connection from the weighted lever to levers which actuate the 85 brake applying devices on the warp beam, said brake applying devices and said warp beam.

3. In loom let-off mechanism, a detector 90 for contacting with the warp on the warp beam, a vertically sliding bar supporting 95 said detector, a horizontally sliding bar, means for connecting said horizontally sliding bar to the vertically sliding bar so that when the horizontal bar is moved so is also the vertical bar, a spring for actuating the horizontal bar, a supporting bracket to which said spring is attached, said bracket also supporting the vertically and horizontally moving bars, a weighted 100 lever connected to the horizontally moving bar so that it is caused to slide over the arm of a lever, said lever, a connection from said lever to levers which apply braking actions to the warp beam and means for regulating the point of attachment of the connection to the weighted lever so that its leverage may be altered and adjusted.

4. In loom let-off mechanism, a detector, a sliding bar carrying said detector, a horizontally moving bar connected to move in unison with the detector moving bar, means for supporting said bars, means for connecting one bar to the other, a spring for operating said bars, connections from said bars to a sliding weight, said sliding weight, a lever 115 upon the arm of which the sliding weight acts, flexible connections from said lever taking around a guide pulley mounted on levers at one end of the loom so that a connection therefrom may be coupled to the levers at the other end of the loom, said connection, said two sets of levers; brake mechanism operated by said two sets of levers so as to retard the rotary motions of the warp beam and said warp beam.

5. In loom let-off mechanism, a detector for contacting with the warp on the warp beam, vertically and horizontally moving rods, the former being arranged to support
5 the detector while the latter is arranged to transmit motion to the former, means for connecting the two sliding bars together, a spring connected to the horizontally moving bar and to a fixed bracket, said fixed bracket,
10 a lever mounted upon said fixed bracket and a weight mounted to slide upon said lever,

means for connecting said weight to the horizontally sliding bar, screw actuated adjusted means for moving and regulating the point of contact of the connection to the weighted lever, means for coupling said adjustable connection on the weighted lever to other levers for actuating brake mechanism, said brake mechanism mounted in conjunction with the warp beam and said warp beam. ¹⁵
